US00D799934S

(12) **United States Design Patent** (10) **Patent No.:** **US D799,934 S**
(45) **Date of Patent:** **** Oct. 17, 2017**

(54) **WALL MOUNTED RECEPTACLE**

(71) Applicant: **Crestron Electronics, Inc.**, Rockleigh, NJ (US)

(72) Inventors: **André Poulheim**, Frechen (DE); **Stefan Kenta Hohn**, Cologne (DE); **Evan Ackmann**, Hoboken, NJ (US)

(73) Assignee: **CRESTRON ELECTRONICS, INC.**, Rockleigh, NJ (US)

(**) Term: **15 Years**

(21) Appl. No.: **29/578,556**

(22) Filed: **Sep. 22, 2016**

(51) **LOC (10) Cl.** **11-05**

(52) **U.S. Cl.**

USPC **D8/353; D13/156**

(58) **Field of Classification Search**

USPC D13/162, 164, 171, 177, 139.1, 139.6, D13/156; D8/350, 353

CPC .. H01H 3/12; H01H 9/02; H01H 9/16; H01H 9/18; H01H 9/181; H01H 9/182; H01H 13/04; H01H 13/14; H01H 2009/187; H01H 23/02; H01H 23/04; H01H 23/08; H05B 33/0803; H05B 33/0863; H05B 37/02; H05B 37/0254; H05B 37/0272; H05B 39/02; H05B 39/04; H05B 39/085; H05B 39/086; H05B 39/088; H01R 13/74; H01R 13/741; H01R 24/64; H02G 3/123; H02G 3/14; H02G 3/18

(57) **CLAIM**

The ornamental design for a wall mounted receptacle, as shown and described.

DESCRIPTION

FIG. 1 shows a front perspective view of a wall mounted receptacle.

FIG. 2 shows a front elevation view of the wall mounted receptacle.

FIG. 3 shows a left side view of the wall mounted receptacle.

FIG. 4 shows a right side view of the wall mounted receptacle.

FIG. 5 shows a top view of the wall mounted receptacle; and,

FIG. 6 shows a bottom view of the wall mounted receptacle.

1 Claim, 8 Drawing Sheets
